UNITED STATES PATENT OFFICE.

JOHN DEWEY HOUSTON, OF PRINEVILLE, OREGON.

COOLING SYSTEM FOR INTERNAL-COMBUSTION ENGINES.

1,391,188.

Specification of Letters Patent. Patented Sept. 20, 1921.

Application filed May 13, 1919. Serial No. 296,856.

To all whom it may concern:

Be it known that I, JOHN DEWEY Houston, a citizen of the United States, residing at Prineville, in the county of Crook and State of Oregon, have invented certain new and useful Improvements in Cooling Systems for Internal-Combustion Engines, of which the following is a specification.

This invention relates to a cooling system for internal combustion engines, and an object of the invention is to provide a system wherein the quantity of the cooling liquid may be varied as conditions warrant, and in which the scope of circulation of the cooling liquid may be varied as necessary.

A further object of the invention is to provide a cooling system for internal combustion engines such as used in airplanes. Also an object of the invention is to eliminate the usual form of "honeycomb" radiators which present considerable head-on resistance to the flight of the airplane, and which cooling system comprises a plurality of relatively thin compartments extended along the fuselage or body, having communication with each other and with the cooling chamber of the engine or motor of the airplane, and also to provide valves by means of which the compartments may be successively cut out, to limit the circulating scope of the cooling liquid, which valves are arranged to drain the compartments as they are cut out of the cooling system, to decrease the weight of the airplane, as a cooling liquid, is unnecessary, when the airplane reaches a high altitude where the air is invariably cold.

Another object of the invention is to provide a cooling system as specified, which might be applied to various types of motor vehicles, and by means of which the quantity of the cooling liquid, and its scope of movement might be varied, to suit different climatic conditions.

Other objects of the invention will appear in the following detailed description taken in connection with the accompanying drawings, forming a part of this specification and in which drawings:

Figure 1 is a longitudinal section through the forward end of an airplane showing the improved cooling system installed thereon.

Fig. 2 is a horizontal section through the front or forward end of an airplane.

Fig. 3 is a cross-section through the airplane showing the improved cooling system applied.

Fig. 4 is a fragmentary view illustrating the manner of operating the valves for controlling the circulation of the cooling liquid.

Fig. 5 is a detailed section of one of the valves, preferably at the upper end of one of the compartments, and

Fig. 6 is a section through one of the valves which is positioned at the lower end of one of the compartments, and permit the draining of the cooling fluid therefrom.

Referring more particularly to the drawings, wherein like characters indicate like and corresponding parts throughout the several views, 10 indicates the fuselage of an airplane, having the usual cock-pit in which the seats 11 and 12 are positioned.

The motor or internal combustion engine 13, of the airplane may be of any approved construction, of the water cooled type having the usual form of cooling chambers, into which the water or cooling fluid enters through the pipe 14 at the lower end of the engine and from which the water or cooling liquid exits through the pipe or conduit 15 at the upper end of the engine.

The improved cooling system, includes a tank or radiator which is carried by the fuselage 10, rearwardly of the engine 13 and which is composed of a plurality of compartments 16, 17, 18 and 19. It is to be understood that any desired number of compartments may be provided, without departing from the spirit of this invention. The various compartments 16, 17, 18 and 19 are relatively shallow, as clearly shown in Fig. 3 of the drawings, so as to cause the water to

pass therethrough in substantially sheet formation to facilitate the cooling of the water prior to its return to the water or cooling chamber of the engine 13. Wires or rods 20 extend partially through the compartment, in spaced relation, to divide the water passing downwardly through the compartment into relatively narrow streams of sheet-like formation thereby further facilitating the cooling of the water. The various compartments, gradually increase in size toward their upper end as shown at 21, and with these enlarged portions, the pipe 22 communicates. The branch pipe 22 has communication with the outlet pipe 15 of the cooling system of the engine 13, and they also have communication with an enlarged portion 21 of the forward compartment 16 of the radiator or cooling chamber as clearly shown in Fig. 1 of the drawings. The

lowermost portion of the compartments are enlarged, to form substantially semi-cylindrical portions as shown at 23, and a pipe 24 communicates with the forward end of this 5 enlarged portion of the foremost compartment 16, the said pipe also having communication with the inlet pipe 14 of the cooling system of the engine 13.

The various compartments 16, 17, 18 and 10 19 are cut off from communication with each other, through valve structures 25 and 26, the former valves being positioned between the adjacent ends of the enlarged portion 21 of the compartments, while the 15 lower valve 26 are placed between the basic ends of the enlargement 23 of the various compartments.

The valves 25, are three-way valves, and the stems 27 thereof have rocking arms 28 20 connected thereto, the free ends of which are forked, for receiving between the arms formed by the forking or bifurcating of the arms, an operating rod 29. The operating rod 29 extends longitudinally of the radiator or various compartments, and has its forward end connected, by means of a slot and pin connection with a hand lever 30. This hand lever 30 may be pivotally mounted as shown at 31, in any desired position, 30 convenient for operation by the pilot or passenger of the airplane, and a quadrant 32 is employed in connection with the lever for holding the same in various adjusted positions to permit regulation of the operation 35 of the various valves of the respective compartments of the radiator structure. The rod 29 has depending nibs or lugs 33 formed thereon, which when the rod 29 is forced rearwardly engage the forked arms 28 and 40 rock the valve stems 27, to operate the valve cones of the upper valves 25 to open them to the atmosphere through openings 34 in the casing of the valve 25 and to cut off communication between the adjacent compartments. The lugs 33 are spaced, along 45 the rod 29, so that the initial movement of the rod will rock the rearmost valve stem 27, and then successively operate the valves 25, toward the forward end of the machine, thus 50 cutting off first the rear-most compartment, next the compartment next to the rear-most, and the various compartments successively until the first and second compartments are cut off.

55 The valve stems 27 of the valve 25 also have rocking arms 35 connected thereto, which arms are connected by means of rods 36 to rocking shafts 37 positioned near the lower portion or bottom of the fuselage. 60 These rods 37 have arms 38 thereon which are connected by means of rods 39, and links 40 to the valve stems of the cones of the lower valve 26, for operating the lower valves of each compartment synchronously 65 with operation of the upper valve of the

said compartment. The valve cones 41 of the lower valve 26 have transverse passageways, provided three-way valves, so as to permit the establishing of communication between the adjacent compartment when the 70 said adjacent compartments are in communication with each other and the water cooling chambers of the engine 13. The casing 42 of the lower valve 26 has communication, through ways 43 with the atmosphere, between the bottom of the fuselage 10, so that when the valves 41 are rocked to cut off communication between adjacent compartments in the system, the rear-most compartment which is cut out, or in other words 75 the compartment directly in the rear of the valve operated will be drained through the port of the valve cone 41 and the port 43, thereby permitting the decrease of the weight of the airplane, by the draining of 80 the cooling fluid which is not in use, therefrom.

The various compartments, have communication, at their upper enlarged portions 21, through branch pipes 44 one at each side of 90 the airplane, in which branch pipes the valves 25 are positioned.

In mounting or climbing, as the temperature of the air decreases, the need of the cooling fluid decreases for properly cooling 95 the engine 13, and consequently by operation of the lever 30, the pilot of the airplane may successively cut out the compartment of the radiator, decreasing the quantity of the cooling fluid circulating through the 100 engine water chamber, and also cutting down the scope of circulation of the cooling fluid, the fluid which is cut out of the engine being drained from the compartment through the drain ways 43, thereby eliminating the 105 necessity of the carrying of unnecessary load by the airplane which would be in the form of the inactive cooling fluid, and when returning to earth, after a flight, as the airplane approaches the earth and the temperature of the air thereabout increases, the engine may be cut off, allowing the airplane to glide to the earth for landing, and as such procedure is the usual thing, the draining 110 of the various compartments in the airplane at a high altitude will in no way interfere with the efficient operation of the airplane.

The cooling system tank or radiator may be filled or recharged in any desired manner, 115 through the filler plug indicated at 45, and if it is so desired, the foremost compartment of the radiator may be drained, by means of a set cock or any other approved desired manner.

While in the foregoing description, and drawings, the cooling system has been described and illustrated as applied to an airplane engine, it is to be understood, that it may be used in connection with motor 130

vehicle engines or with any kind of internal combustion engine for regulating and varying the quantity and scope of circulating movement, of the cooling fluid used with the 5 engine, in accordance with climatic conditions.

Changes in details may be made without departing from the spirit of this invention, but:

10 I claim:

1. The combination with an internal combustion engine having a cooling chamber, of a radiator comprising a plurality of compartments, means establishing successive 15 communication between said compartments, conduits establishing communication between said radiator and the cooling chamber of said engine, and means whereby certain of said compartments may be cut out 20 of operative communication with said cooling chamber.

2. The combination with an internal combustion engine having a cooling chamber, of a radiator comprising a plurality of compartments, means establishing communication between said compartments, conduits establishing communication between said radiator and the cooling chamber of said engine, means whereby certain of said compartments may be cut out of operative communication with said cooling chamber, and means connected to said last named means for automatically draining the compartments as they are cut out of operative communication 30 with the cooling chamber.

3. In a cooling system for internal combustion engines, a radiator comprising a plurality of compartments, and valves establishing communication between said compartments at the upper and lower ends thereof, the valve casings of said valves also having communication with the atmosphere exteriorly of the radiator whereby when one compartment is cut off from circulating communication with a compartment of the radiator the fluid therein will be drained from the compartment.

4. In a cooling system for internal combustion engines, a radiator comprising a plurality of compartments arranged successively throughout the length of the radiator, valves establishing communication between the adjacent compartment, and means for successively operating said valves to successively cut out the various compartments of the radiator from circulating communication, said valve including casings having communication with the atmosphere exteriorly of the radiator whereby the compartment cut out of the circulating communication will be drained of cooling fluid.

5. In an airplane, the combination with an internal combustion engine having a cooling chamber, of a radiator, and means establishing circulating communication between said

radiator and engine, said radiator being extended along the fuselage rearwardly of the engine and interiorly of the fuselage, to provide a relatively shallow compartment through which cooling fluid will circulate in 70 sheet like form.

6. In an airplane, the combination with an internal combustion engine having a cooling chamber, of a radiator, means establishing circulating communication between 75 said radiator and engine, said radiator being extended along the fuselage rearwardly of the engine and interiorly of the fuselage, to provide a relatively shallow compartment 80 through which cooling fluid will circulate in sheet like form, and a plurality of dividing rods in said radiator to divide the cooling fluid into streams of sheet-like forms.

7. In an airplane, the combination with an internal combustion engine having a cooling chamber, of a radiator, means establishing circulating communication between said radiator and engine, said radiator being extended along the fuselage rearwardly of the engine and interiorly of the fuselage, to provide a relatively shallow compartment 85 through which cooling fluid will circulate in sheet like form, a plurality of dividing rods in said radiator to divide the cooling fluid into streams of sheet-like forms, said radiator comprising a plurality of compartments, and valves establishing circulating communication between said compartments. 90

8. In an airplane, the combination with an internal combustion engine having a cooling chamber, of a radiator, means establishing circulating communication between said radiator and engine, said radiator being extended along the fuselage to provide a relatively shallow compartment through which 100 cooling fluid will circulate in sheet like form, said compartment enlarged at its upper edges, and conduits communicating with said enlarged portions, and with the outlet of the cooling system of the engine. 105

9. In an airplane, the combination with an internal combustion engine having a cooling chamber, of a radiator, means establishing circulating communication between said radiator and engine, said radiator being extended along the fuselage to provide a relatively shallow compartment through which cooling fluid will circulate in sheet like form, said compartment enlarged at its upper edges, conduits communicating with 110 said enlarged portions, and with the outlet of the cooling system of the engine, said compartment being enlarged at its lowermost portion, conduits communicating with said lowermost enlarged portions, and with 120 the inlet of the cooling system of the engine, and means for varying the circulating scope of the cooling fluid through said radiator. 125

10. In an airplane, the combination with an internal combustion engine having a 130

- cooling chamber, of a radiator, means establishing circulating communication between said radiator and engine, said radiator extending along the fuselage to provide 5 a relatively shallow compartment through which cooling fluid will circulate in sheet-like form, and means in said compartment to divide the cooling fluid circulated therethrough in relatively narrow thin streams.
- 10 11. In an airplane, the combination with an internal combustion engine having a cooling chamber, of a radiator, means establishing circulating communication between said radiator and engine, said radiator extending along the fuselage to provide 15 a relatively shallow compartment through which cooling fluid will circulate in sheet-like form, means in said compartment to divide the cooling fluid circulated therethrough in relatively narrow thin streams, and means for varying the circulating scope 20 of the cooling fluid through said radiator.
12. In a cooling system for internal combustion engines, a radiator comprising a plurality of compartments, valves establishing communication between said compartments at the upper and lower ends thereof, the 25 valve casings of said valves having communication with the atmosphere exteriorly 30 of the radiator whereby when one compartment thereof is cut off from circulating communication with an adjacent compartment of the radiator, the fluid therein will be drained from the cut off compartment, said 35 compartment being extended to provide relatively shallow compartments through which the cooling fluid will circulate in sheet like form.
13. In a cooling system for internal combustion engines, a radiator comprising a plurality of compartments, valves establishing communication between said compartments, 40 means at the upper and lower ends thereof, the valve casings of said valve having communication with the atmosphere exteriorly 45 of the radiator whereby when one compartment thereof is cut off from circulating communication with an adjacent compartment of the radiator, the fluid therein will be drained from the cut off compartment, said compartment being extended to provide relatively shallow compartments through which the cooling fluid will circulate in sheet like form, and means in said compartments to divide the cooling fluid circulating therethrough in relatively narrow thin streams. 50
14. In a cooling system for internal combustion engines, the combination with an internal combustion engine of the water cooled type, of a radiator therefor, formed of a plurality of compartments, valves establishing communication between said compartments, an operating lever, and means connecting said operating lever and valves, 55 whereby said lever may be operated for cutting off any number of the compartments from communication with said internal combustion engine. 60
15. In a cooling system for internal combustion engines, the combination with an internal combustion engine of the water cooled type, of a radiator therefor formed of a plurality of compartments, valves establishing communication between said compartments, an operating lever, and means connecting said operating lever and valves, 65 whereby said lever may be operated for cutting off any number of the compartments from communication with said internal combustion engine, said means adapted to position certain of said valves for draining the 70 contents of certain of said compartments. 75
- JOHN DEWEY HOUSTON. 80
